CLAMP DEVICE FOR HAIR TINTING

Gertrude M. Hoffman, Omaha, Nebr.

Original application November 7, 1941, Serial No.
418,175. Divided and this application June 15,
1942, Serial No. 447,125

14 Claims. (Cl. 132—9)

This invention relates to new and useful improvements in clamp devices for hair tinting.

One of the objects of my invention is to provide simple, efficient and adjustable clamping means whereby comparatively thin strands of tinted or dyed human hair may be tightly clampingly engaged and readily adjustably supported upon the head to conveniently permit the portions of the new growth of hair in such strand, near the roots of the hair, to be treated with a bleach or tonic, or tinted or dyed to compensate for such growth subsequent to the initial dyeing of the hair.

Another object of my invention is to provide elongated clamping means in the form of a unitary partially longitudinally split bar, cooperating with pressure-applying means, for retaining a strand of hair during treatment of a section of such strand.

Another object of my invention is to provide such adjustably-supported clamping means in the form of hingedly connected pairs of cooperating bars of non-porous and non-absorbing material, preferably resilient material such as rubber, although non-absorbent fiber may be used, or other suitable plastic composition. Such bars being preferably elongated and of both straight and slightly arcuate shapes, and including clamps for tightly clamping together each pair of the strand-engaging bars to thereby prevent seepage therebetween of the dyeing solution onto the portion of the strand of the dyed hair which is clamped between such bars so that the new growth of hair near the roots may be neatly dyed without streaking and without double-tinting portions of the originally tinted hair which is securely held between the bars; such bars, the clamps therefor, and their adjustable supports being preferably of a rubber or fiber composition which is not effected by the dye or tinting solution to thereby obviate any chemical reaction or undesirable effect upon the hair, in other words, for practical purposes, I prefer to make most of the parts of my improved device of non-metallic material and where metallic parts are used to impart strength, such metallic parts may preferably be coated with rubber or with a pressed fiber composition which is not effected by or non-reactive to dyes.

Another feature of my invention is found in the undulating formation of the complementary clamping faces of the strand-engaging and supporting bars whereby the strand of hair is not only more securely retained thereby but which wavy form of the bar faces facilitates the tint-

ing or treating operation of a desired portion of the strand.

With the above and other objects in view which will readily become apparent from the perusal of the following specification and attached drawing, my invention consists in the novel combination, construction and arrangement of the parts and members shown in preferred embodiments in the attached drawing, described in the following specifications, and particularly pointed out in the appended claims.

In the drawing:

Fig. 1 is a side elevation of a clamp device embodying my invention for tinting or treating hair;

Fig. 2 is a plan view of the device shown in Fig. 1;

Fig. 3 is a vertical cross-section taken on line 3—3 of Fig. 1;

Fig. 4 is an end view of a rubber-covered resilient clamp which may be employed in the clamp device illustrated in Figs. 1, 2 and 3;

Fig. 5 is a side elevation of the clamp device but embodying a modification of my invention showing straight bars;

Fig. 6 is a plan view of the clamp device shown in Fig. 5;

Fig. 7 is a side elevation of a clamp device for tinting or treating hair embodying another modification of my invention but showing the two strand-supporting bar members embodied in a unitary split bar;

Fig. 8 is a plan view of the device shown in Fig. 7;

Fig. 9 is a vertical cross-section through the clamp shown in Figs. 7 and 8 taken on line 9—9 of Fig. 7;

Fig. 10 is a side elevation of a pair of strand-engaging bars wherein the hinge pin is disposed transversely to the planes of the parallel strand-engaging bars; and

Fig. 11 is a vertical cross-section taken on line 11—11 of Fig. 10.

Fig. 12 shows a portion of the strand-engaging face of one of the bars shown in Fig. 1.

Figs. 1 to 4 inclusive show my invention applied to a pair of strand-supporting bars of elongated arcuate shape, and Figs. 5 to 11 inclusive show my invention applied to pairs of strand-supporting bars of elongated but straight form.

The bars illustrated in Figs. 1, 2, 3, 5 and 6 are adapted to be clampingly secured together by clamps which are applied transversely to the longitudinal axes of the bars and preferably at

or near the opposite ends of the bars. A preferred type of such clamp is illustrated in Fig. 4.

The bars illustrated in Figs. 7 to 11 inclusive are adapted to be clampingly secured together by clamps which are applied preferably from opposite ends of the bars and which clamps are of the type illustrated in Figs. 7, 8 and 9.

In the illustrations, like reference characters indicate like or corresponding parts or members.

The embodiment of my invention illustrated in Figs. 1, 2, 3 and 4 consists of a pair of elongated, slightly arcuate, bars 20 having preferably undulating adjacent inner contact faces 21 of complementary formation to interfit one another; the undulations being slightly curved on radii whose center is the pivot 26, as shown in Fig. 12.

While the bars 20 are shown in slight arcuate formation somewhat conforming to the curve of the top of a human head, these bars 20 may be straight bars 20¹ such as shown in Figs. 5 and 6, likewise, the hair strand clamping faces 21 may be plane-aligned surfaces 23 as shown in Figs. 7 to 11 inclusive, although I prefer to use the slightly undulating contact faces 21.

The two strand-supporting bars 20 are preferably of trapeziform cross-section.

The end surface portions of the outer faces are preferably roughened or serrated or provided with a series of longitudinally extending tooth-like formations 22 to provide resistance to the upward movement of the two V-shaped clamps 25 made of resilient metal 25^M embedded in molded rubber 25^R, as shown in Fig. 4, and having serrated portions 25^S.

The clamps 25 may also be made of uncovered metal, as shown in Figs. 1 to 3 inclusive, each clamp 25 consisting of a strip of steel formed into a clamp of V-shaped cross-section having angularly flanged ends 25^A and having roughened or preferably tooth-like formations 25^B formed on portions of the opposed inner faces.

When the strand of hair 24 is interposed between these two bars 20, the clamps 25 are forcibly slidably mounted upon the serrated ends 22 to tightly engage the strand of hair disposed between their undulating inner faces. The resistance between the clamp teeth 25^B and the serrations 22 retains the clamps 25 in adjusted positions thereon and the clamp flanges 25^A form suitable supports for retaining the device upon the head. The resiliency of the clamps 25 permits their adjustment vertically relatively to the longitudinal axis of the two bars for proper alignment with the line of the untinted growth of hair.

The bars 20 may be made in the form of separate bars secured together in clamping position about the strand of hair 24 by the clamps 25. The bars 20 may also be hingedly connected together at a pair of adjacent ends of such bars, as by a hinge pin 26 disposed transversely to the vertical planes of the undulating faces, so that one bar may be swung about such hinge upwardly, in the plane of the undulating faces, relatively to the other bar when applying the bars to a strand of hair.

The above described hinge connection 26 is also employed in the illustrations of the two plain or straight-faced bars 27, shown in Figs. 10 and 11, wherein the employed hinge is shown in Fig. 11, in more detail, as comprising a pin 26 having countersunk rivet-headed ends extending over the ends of the bearing sleeves 28 molded into the adjacent hinged ends of the bars 27. The hinge pin 26 extends through the sleeves 28. 75

Figs. 5 and 6 illustrate a pair of strand-engaging bars 20¹ of a type similar to the bars 20 illustrated in Figs. 1 to 3 inclusive, however, these bars 20¹, as shown in Figs. 5 and 6, are not arcuate but are straight and hingedly connected together at one end with a hinge generally designated by numeral 29. The hinge 29 consists of a plate portion 30 embedded or molded within each bar 20¹; one hinge plate portion 30 is provided with an integral perforated ear 31 extending beyond the end of its supporting bar 20¹. The perforated ear portion 31 is embraced between the two spaced perforated ears 32 formed integrally with the plate portion 30 embedded within the other bar 20¹, and the ears 31 and 32 are hingedly interconnected by the hinge or pivot pin 33 which extends through the perforations of the ears.

It will be noted that the hinge pin 33 for the bars 20¹, shown in Figs. 5 and 6, is disposed parallel to the strand-engaging faces 21 and not transversely to such faces 21 as in the case of the hinge pin 26 shown in Figs. 1 and 10, and therefore the spreading-apart movement of the bars 20¹ is in the direction shown by the arrows in Fig. 6.

The bars 27, shown in Fig. 10, are rectangular in cross-section, as shown in Fig. 11, and the outer sides or faces of these bars 27 are provided with wedge-like formations 34 formed preferably integrally with the bars and each increasing in cross-sectional thickness inwardly or toward the center of the bar and each formation 34 being preferably narrower in width than the width of the face of the bar from which such formations project outwardly.

In the modification of my invention as illustrated in Figs. 7, 8 and 9, the unitary strand-engaging bar 35 consists of a single piece of molded or cast rubber or other suitable non-porous, or non-absorbing composition of matter.

The bar 35 is divided longitudinally, mechanically or otherwise, to provide a pair of bar sections 35^A integrally connected at one end of the bar 35, as at 35^B. These sections may be formed in the molding operation or the bar 35 may be cast or molded in one piece and then split by cutting or sawing operation through the greater portion of its length, the split or cut terminating in a preferably tubular slot 36 to reduce the possibility of rupture at such end of the split portion.

While the bar portions 35^A are shown provided with straight or plane-aligned strand-engaging faces 23, these faces 23 could obviously be molded with the undulating surfaces 21 shown in Fig. 6, furthermore, the unitary bar 35 is shown as a straight bar but same could obviously be molded in arcuate configuration similar to the bars 20 shown in Figs. 1 and 2. The two bar sections 35^A are of rectangular cross-section as shown in Fig. 9, but these sections could readily be formed of trapezi-form cross-section, as shown in Fig. 3.

As shown in Figs. 7, 8 and 9, the strand of hair 24, which is to be treated or tinted, is embraced between the faces 23 of the bar sections 35^A and the two bar sections are then tightly clampingly secured together by the clamps 37 which are slidably moved over the wedge-like formations 34 inwardly from the ends of the bar 35 to thereby firmly press the bar sections 35^A toward each other to tightly secure the strand of hair disposed between them and thus prevent seepage of the dye onto the previously dyed hair held between them.

Since the rate of growth of human hair is substantially uniform the split bar 35 is so applied to the strand of hair that the line of the new growth is substantially aligned with the bottoms 35^c of the sections 35^a to thus establish a guide for the operator performing the tinting or treating operation.

The clamps 37 are of U-shaped and each clamp is formed with spaced arms 38 having channeled inner sides to fit the wedges 34, as shown in Fig. 9. The arms 38 are formed integrally with the back portion 39 which is threaded to receive an adjustable screw support 40 having a knurled head 41 and the lower end rotatably connected with a supporting base 42.

To facilitate the tinting of the new growth of hair, the screws 40 are adjusted to extend the strand of hair 24 in raised or stretched position upon the spaced three-legged bases 42 which rest upon the head.

The screw 40 and base 42 may be made of metal but I prefer to make both of these parts of a highly compressed fiber composition.

It is obvious, to those skilled in the art to which my invention appertains, that the devices described and claimed herein are applicable to bleaching, ointment or tonic treatments as well as to dyeing of hair, and therefore, in each instance where the word "dyeing" is used, the same shall be construed to include bleaching, and ointment or tonic treatments and that throughout the specification and claims the word "dyeing" or "tinting" is synonymous with bleaching, or ointment or tonic treatments.

It is also obvious that the particular details of construction and arrangement of the parts and members, shown in the drawing and described in the specification by way of illustration of preferred embodiments of my invention, may be varied without departing from the spirit of my invention which is defined in the appended claims.

This application is a division in part of my pending application Serial No. 418,175 filed Nov. 7, 1941.

I claim:

1. A device for use in dyeing hair comprising an elongated instrumentality of resilient non-porous material adapted to engage a strand of dyed hair between portions thereof to present the new growth of the undyed strand portion between said instrumentality and the scalp, and clamp means for clamping retaining said strand-engaging portions of said instrumentality in gripping engagement with the strand of hair.

2. A device for use in dyeing hair as embodied in claim 1, and including means for adjustably supporting said instrumentality on a person's head to thereby retain said undyed strand portion in stretched position to facilitate the dyeing thereof.

3. A device for use in dyeing hair as embodied in claim 1, and including said strand-engaging portions of said instrumentality having adjacent faces of undulating surface formation, said undulating surfaces being disposed in complementary relatively interengaged arrangement.

4. A device for use in dyeing hair comprising a pair of elongated adjacent bars of rubber of trapeziform cross-section having end portions of their outer faces of serrated formation and their inner adjacent faces of undulating formation adapted to engage therebetween a strand of dyed hair and to present the new growth of the undyed strand portion between said bars and the

scalp for dyeing thereof, and a pair of metallically reenforced rubber clamps of V-shaped cross-section having inner faces provided with serrated portions adapted to engage the said serrated bar portions and to clampingly retain said bars in gripping engagement with the strand of hair.

5. A device for use in dyeing hair as embodied in claim 4, and including the serrated formations on said outer bar faces disposed longitudinally of said bars, and said clamps disposed transversely of said bars and extending below said bars to thereby support said bars on a person's head and to retain said undyed strand portion in stretched position to facilitate the dyeing thereof.

6. In a device for hair dyeing, a pair of bars of non-absorbent material hingedly connected together at one end and adapted to engage a strand of hair between them, clamping means adapted to retain the adjacent faces of said bars in pressure-gripping engagement with the strand of hair to prevent seepage of the dye therebetween, and means associated with said clamping means for supporting said bars on a person's head.

7. A device for hair dyeing, comprising a unitary elongated flexible bar having separated adjacent portions adapted to engage a strand of hair between said portions, clamping means adapted to retain said bar portions in pressure-gripping engagement with the strand of hair, and supporting means associated with said clamping means and disposed at the ends of the unitary bar for supporting the unitary bar on a person's head in spaced position above the scalp.

8. In a device for hair dyeing as embodied in claim 7, and including said supporting means being adjustable for adjustably supporting said unitary bar on a person's head in a selectively spaced position above the scalp.

9. A device for use in hair dyeing, comprising a unitary flexible bar having separable adjacently aligned portions adapted to engage a strand of hair between said portions to present the new growth of the undyed strand portion between said aligned bar portions and the scalp for dyeing thereof, said bar portions being integrally connected at one end, the outer face of each of said bar portions having oppositely disposed wedge-like formations integral with the bar portion, and U-shaped clamps adapted to be slidably mounted over pairs of said wedge-like formations for clamping retaining said bar portions in pressure-gripping engagement with the strand of hair.

10. A device as embodied in claim 9, and including a screw-adjustable supporting member in threaded engagement with each of said clamps adapted for adjustably supporting the unitary bar on a person's head to thereby retain said undyed strand portion in stretched position to facilitate the dyeing thereof.

11. In a device for use in hair dyeing, a pair of elongated bars adapted to engage a strand of dyed hair between them to present the new growth of the undyed strand portion between the said bars and the scalp for dyeing thereof, the outer face of each of said bars having oppositely disposed wedge-like integral formations, a U-shaped clamp slidably mounted from each end of said pair of bars onto said wedge-like formations for clamping retaining said bars in gripping engagement with the strand of hair, a screw adjustable supporting member in threaded engagement with each of said clamps for adjust-

ably supporting said clamped bars on a person's head to thereby retain said undyed strand portion in stretched position to facilitate the dyeing thereof, and means for pivotally connecting said bars at one end thereof.

12. In a device as embodied in claim 11, including said means for pivotally connecting said bars having a pivot pin disposed transversely to the plane of the parallel strand-engaging faces of said clamp bars.

13. In a device for use in hair dyeing as embodied in claim 1, and including said instrumen-

tality comprising a pair of elongated bars pivotally connected together at one end by a pivot pin which is disposed parallel to the strand-engaging faces of said bars.

5 14. In a device for use in hair dyeing as embodied in claim 1, and including said instrumen-tality comprising a pair of elongated bars pivotally connected together at one end by a common pivot pin which is disposed transversely to the 10 plane of the parallel strand-engaging faces of said bars.

GERTRUDE M. HOFFMAN.
